(57) CLAIM

I claim the ornamental design for a light fixture, as shown and described.

DESCRIPTION

FIG. 1 is a perspective view of an embodiment of an ornamental design for a light fixture;

FIG. 2 is a top plan view thereof;

FIG. 3 is a left side elevation view thereof;

FIG. 4 is a right side elevation thereof; and,

FIG. 5 is a rear elevation thereof.

The broken lines showing in FIG. 1, FIG. 3, and FIG. 4 are presented for illustrative purposes only and form no part of the claimed design.
